UNITED STATES PATENT OFFICE

173,166

LENS PANEL FOR DIRECT LIGHTING FIXTURES

Robert G. McPhail, Newark, Ohio, assignor to Holophane Company, Inc., New York, N. Y., a corporation of Delaware

Application August 11, 1953, Serial No. 26,400

Term of patent 14 years

(Cl. D48—23)

To all whom it may concern:

Be it known that I, Robert G. McPhail, a citizen of the United States of America, and a resident of Newark, county of Licking, State of Ohio, having invented a new, original, and ornamental Design for a Lens Panel for Direct Lighting Fixtures, of which the following is a specification, reference being had to the accompanying drawings, forming a part thereof.

In the drawings:

Figure 1 is a perspective view of the lens panel for direct lighting fixtures showing my new design;

Figure 2 is an enlarged bottom plan view of the area bounded by the lines 2—2 of Figure 1;

Fig. 3 is a fragmentary cross sectional view to a larger scale taken on line 3—3 of Fig. 2;

Fig. 4 is a fragmentary cross sectional view to a larger scale taken on line 4—4 of Fig. 2; and

Fig. 5 is a fragmentary cross sectional view to a larger scale taken on line 5—5 of Fig. 2.

The design forming the subject-matter of the present invention is for a lens panel for direct lighting fixtures, the panel being of arbitrary over-all length and width.

The design is characterized by diagonally disposed, checkerboard-like areas, one diagonal row of such areas having each of the lenticulations therein of smaller dimension than the lenticulations of the adjacent diagonal row.

I claim:

The ornamental design for a lens panel for direct lighting fixtures, as shown and described.
